US00D739614S

(12) **United States Design Patent**
Ausman et al.

(10) **Patent No.:** **US D739,614 S**
(45) **Date of Patent:** **** Sep. 22, 2015**

(54) **FEEDING STATION**

(71) Applicant: **Lioness Feeding Technology Inc.**,
Fergus (CA)

(72) Inventors: **Brian Ausman**, Fergus (CA); **Christine Stec**, Fergus (CA)

(73) Assignee: **Lioness Feeding Technology Inc.**,
Fergus, ON (CA)

(**) Term: **14 Years**

(21) Appl. No.: **29/520,479**

(22) Filed: **Mar. 13, 2015**

(51) LOC (10) Cl. **30-07**

(52) U.S. Cl.

USPC **D30/122**; D30/133; D30/121

(58) **Field of Classification Search**

USPC ..... D30/121, 122, 129–133, 108, 110, 111, D30/113, 115, 117, 118, 120, 112; 119/61.5, 51.01, 61.56, 51.03, 59, 62, 119/63, 51.5, 57.8, 74, 61.54, 61.55, 53, 119/53.5, 75, 56.2, 51.02, 51.11, 51.12, 119/57.1, 52.1, 51.5, 429, 457, 484, 489, 119/496, 519, 161, 163, 165, 416–419, 427, 119/428, 433–435, 452, 454, 470, 476, 482, 119/498; 312/204; 248/151, 188; 108/153.1–157; 220/23.87, 630, 737, 220/743, 9.4, 495.01, 574, 212, 255, 23.83; 206/515; D7/586, 543, 550.1, 587, D7/505, 584, 545, 500, 553.1–553.8, 546, D7/555, 556, 504, 565, 562, 602, 605, 312, D7/313, 320, 307, 306, 309, 354, 311, 399, D7/397, 323, 332, 331, 347, 346, 322, 318, D7/317, 316, 619.1; D9/429; 43/109; D22/122; 99/430, DIG. 15, 280, 285, 99/312; 222/209, 131, 363, 349, 517, 222/153.13, 401, 1, 146.5, 23, 54, 64, 51, 222/156, 399, 400.8; 219/438, 439, 441, 219/385, 386, 402, 407; 210/94, 184, 474, 210/477; D25/16, 18, 19, 31, 7, 13–15, 17,

(57) **CLAIM**

The ornamental design for a feeding station, as shown and described.

DESCRIPTION

FIG. 1 is a perspective view of a feeding station; FIG. 2 is a front view of the feeding station; FIG. 3 is a rear view of the feeding station; FIG. 4 is a left side view of the feeding station; FIG. 5 is a right side view of the feeding station; FIG. 6 is a top view of the feeding station; and, FIG. 7 is a bottom view of the feeding station.

1 Claim, 4 Drawing Sheets
